Chapman Hosmer & Co
Attest

United States Patent Office.

FRANZ DIEBOLD, OF BOSTON, MASSACHUSETTS.

Letters Patent No. 78,937, dated June 16, 1868.

IMPROVED WASH-BENCH.

The Schedule referred to in these Letters Patent and making part of the same.

TO WHOM IT MAY CONCERN:

Be it known that I, FRANZ DIEBOLD, of the city of Boston, and State of Massachusetts, have invented a new and valuable Improvement in Wash-Benches; and I do hereby declare that the following is a full, clear, and exact description of the construction and operation of the same, reference being had to the annexed drawings, making a part of this specification, and to the letters and figures of reference marked thereon.

The nature of my invention consists in constructing and arranging three bars of wood, with two legs attached to each thereof, in such manner that, when united, they shall form convenient supports for two wash-tubs; and it further consists in so constructing and arranging the several bars that two of them may be united, and thereby form a convenient support for one wash-tub.

Letter A of the drawings represents the long or main bar of my wash-bench. It has one mortise on its upper side, and one on its lower side, as shown, to form the proper connections with the cross-bars B and C, as hereinafter stated.

Letters B and C are cross-bars, attached to the long bar A by mortises, in the manner represented on Figure 1 of the drawings, whenever I desire to form a support for two wash-tubs.

Figure 2 of the drawings is a representation of the cross-bars B and C, detached from the long bar A, and united, to form a bench for a single tub.

Letters D are pins attached to the several bars, and serve to hold the tub securely on the bench.

My device is operated as follows:

Place the bar A on its legs, and attach thereto the cross-bars B and C, in the manner shown on fig. 1. By these means neat and convenient benches are formed for two wash-tubs.

Again, place the cross-bars B and C together, in the manner shown on fig. 2, and thereby a neat and convenient bench is formed for a single tub.

What I claim as my invention, and desire to secure by Letters Patent, is—

The combination and arrangement of the bars A, B, and C with the pins D, and the necessary legs, for the purposes specified.
